(57) **CLAIM**

The ornamental design of a toilet seat protector, as shown and
described.

DESCRIPTION

FIG. 1 is a top perspective view of a toilet seat protector of the
present invention;

FIG. 2 is a top plan view of the toilet seat protector of FIG. 1,
FIG. 3 is a bottom plan view of the toilet seat protector of FIG.
1; and,

FIG. 4 is a bottom perspective view of the toilet seat protector
of FIG. 1.

The broken lines showing a toilet in FIG. 1 are for illustrative
purposes only and form no part of the claimed design.

The broken lines showing a toilet seat in FIG. 4 are for
illustrative purposes only and form no part of the claimed
design.

1 Claim, 4 Drawing Sheets
